COMBINED TEA CART AND PORTABLE DISHWASHER

Wallace H. Appel and Carl A. Peterson, Columbus, Ohio,
assignors to Westinghouse Electric Corporation, a cor-
poration of Pennsylvania

Filed Aug. 2, 1967, Ser. No. 8,101

Term of patent 14 years

(Cl. D49—1)

FIG. 1.

FIG. 2.

FIG. 3.

FIG. 4.

FIG. 5.

FIG. 6.

FIGURE 1 is a perspective view of a combined tea cart and portable dishwasher embodying our new design; FIG. 2 is a top plan view thereof;

FIG. 3 is a front elevational view thereof;

FIG. 4 is a side elevational view thereof, taken from the right of FIG. 1;

FIG. 5 is a rear elevational view thereof; and

FIG. 6 is a side elevational view thereof, taken from the right of FIG. 1, showing the lid in partially raised position.

The dominant feature of our design resides in the portions shown in full lines.

We claim:

The ornamental design for a combined tea cart and portable dishwasher, substantially as shown and described.
